UNITED STATES PATENT OFFICE

172,249

AUTOMOBILE OR SIMILAR ARTICLE

Renzo Rivolta, Bresso, Italy

Application June 16, 1953, Serial No. 25,525

Term of patent 14 years

(Cl. D14—3)

To all whom it may concern:

Be it known that I, Renzo Rivolta, a citizen of the Republic of Italy, residing at Bresso (Milan), Italy, have invented a new, original, and ornamental Design for an Automobile or Similar Article, of which the following is a specification, reference being had to the accompanying drawing, forming a part thereof.

Fig. 1 is a side elevational view of an automobile or similar article, showing my new design;

Fig. 2 is a plan view thereof; and

Fig. 3 is a front elevational view thereof.

I claim:

The ornamental design for an automobile or similar article, substantially as shown.
